LIQUID LEVEL GAUGE HEAD

Jehu Morphis, Garland, Tex., assignor, by mesne assignments, to Leta S. Taylor, individually and as trustee

Application May 22, 1956, Serial No. 41,599

Term of patent 14 years

(Cl. D52—1)

Fig. 1.

Fig. 2.

Fig. 3.

Fig. 1 is a top plan view of a liquid level gauge head embodying the design;

Fig. 2 is a perspective view thereof; and

Fig. 3 is a side view thereof.

In the drawing, the characteristic features of the design are shown in full lines.

I claim:

The ornamental design for a liquid level gauge head, substantially as shown and described.
